UNITED STATES PATENT OFFICE.

ADOLPH M. HOLSTEIN, OF SYRACUSE, NEW YORK.

DESIGN FOR A CORNER-PIECE FOR COFFINS AND CASKETS.

46,825.

Specification for Design.

Patented Jan. 5, 1915.

Application filed September 11, 1914. Serial No. 861,311. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design for a corner piece for coffins comprises angularly arranged lengthwise faces having a lengthwise embossed figure 1 at their juncture, and lengthwise curved depressions 2 at opposite sides of the intermediate portion of the figure 1. The embossed figure 1 is of greatest width at its bottom and is spherical in form at its lower end. Above its spherical lower end the embossed figure 1 is in the form of a stem rounding in cross-section, and of enlarged width between its ends, and contiguous outer

surfaces of said spherical lower end and the stem curve inwardly or rearwardly toward each other and merge together in a concave surface. The upper portions of the outer edges of the depressions 2 extend outwardly in concave lines from the central part of the corner piece and the lower portions of said edges extend outwardly in convex lines and terminate in lines extending inwardly toward the spherical end of the figure 1. Above the embossed figure 1 and the depressions 2 are lobes 3.

I claim:

The ornamental design for a corner piece for coffins and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.

Witnesses:

S. DAVIS,
F. B. PICKARD.
